UNITED STATES PATENT OFFICE.

EUGENE F. BOWEN AND EPHRIAM J. SCOTT, OF PROVIDENCE, RHODE ISLAND.

STAMP-AFFIXING MACHINE.

Application filed September 17, 1920. Serial No. 410,905.

To all whom it may concern:

Be it known that we, EUGENE F. BOWEN and EPHRIAM J. SCOTT, citizens of the United States, and residents of the city of Providence, in the county of Providence and State of Rhode Island, have invented certain new and useful Improvements in Stamp-Affixing Machines, of which the following is a specification.

10 This invention relates to stamp-affixing machines, and has for one of its objects to provide a machine of this character having a plunger which is operated indirectly through the movement of a hand lever.

15 A further object of the invention is to provide means whereby the strip is advanced upon the return stroke of the plunger and the feeding mechanism is returned to the beginning of its feeding stroke upon 20 the affixing stroke of the plunger.

25 A further object of the invention is to provide a pressure pad on the plunger with a plurality of spaced-apart flexible teats or projections on its engaging surface whereby said surface will readily accommodate itself to the uneven surface of the package while in the act of applying a stamp thereto.

It is found in practice that where the affixing plunger is provided with a presser head to be engaged and directly operated by the hand of the operator that oftentimes it is struck a quick blow by the open palm or fist by unthinking or unauthorized persons, the same as they would strike a punching or cutting machine, but in a stamp feeding machine such a blow is apt to cause the feeding fingers to jump and tear the stamps, and accurate feeding under such conditions is not found possible. Therefore, to obviate this difficulty, I have removed the cap or head from the plunger and have connected an operating handle to the lever shaft whereby the operator will naturally take hold of the lever and operate it as is intended, thus obtaining the best results from the operating mechanism.

Another feature of the invention is that the feeding stroke in this machine is actuated by the upward or return movement of the handle so that even if the operating handle were forced too quickly downward it would not affect the feeding action of the mechanism.

55 Then again, by this construction and ar-

angement for operating the strip-feeding mechanism the number of operating parts is reduced to the minimum.

With these and other objects in view, the invention consists of certain novel features 60 of construction, as will be more fully described and particularly pointed out in the appended claims.

In the accompanying drawings:

Figure 1 is a side elevation showing the 65 frame or casing in section, the plunger in its raised position and the strip-feed in advance position.

Figure 2 is a view of the operating mechanism showing the plunger in down position 70 and the feeding mechanism in back position ready to begin its feeding stroke.

Figure 3 is a perspective view illustrating the hand-operating lever mounted on a transverse shaft also the feed-actuating leg 75 and arm for engaging the plunger, both also mounted on and connected to said shaft whereby they may be operated by said lever.

Figure 4 is a detail in perspective illustrating the feeding pawls mounted to be 80 moved over the stamp strip supporting table.

Figure 5 is a perspective view of the engaging face of the presser pad showing the 85 protruding teats thereon.

Referring to the drawings, 10 designates the casing for a stamp-affixing machine, which may be made in any desired shape or size. A substantially semi-cylindrical cap 11 is hinged at 12 to the rear of the casing 90 and is adapted to be swung back to permit the roll of stamps 13 to be mounted in the casing on the pin 14. The top portion 15 of the casing extends upward and forward where it is constructed to provide a vertical 95 bearing for the plunger 16.

A cap or hood 17 is provided to completely enclose this plunger and provide additional bearing therefor. The plunger 16 has an aperture 18 in its upwardly extending portion for the reception of the operating lever presently described, and the lower portion of the plunger is provided with an enlarged foot 19 to which is attached a pad 20, the lower portion of the pad being provided 100 with a plurality of spaced apart outwardly-projecting, flexible or yieldable teats or 105 protuberances 21 whereby the face of the pad is adapted to readily yield and accommodate itself to the face of the package to which the 110

stamp is being applied even though that face be extremely uneven.

A hood or jacket 22 is fixed around the foot of the plunger to enclose the stamp 5 which may be advanced from the coil and protect the same from being surreptitiously removed by unauthorized persons.

A knife blade 23 is secured to and carried by the foot of the plunger so that as it descends it moves along the inner surface of the plate 24 and engages the edge of the corresponding blade 25 located below the line of the stamp strip whereby the downward movement of the plunger causes the blades 15 to sever the stamp which is immediately engaged and affixed to the package.

A table 26 is provided to support the strip of stamps in moving from the reel or roll 13 to the cutter 25.

20 The strip of stamps as is well known, is usually perforated between the stamps, and therefore I have provided a plurality of small fingers 27 loosely mounted on the pin 28 on the lever 29 and their engaging ends 25 are normally held in contact with the strip by means of springs 30, the opposite ends of which are connected to the pin 31 also on said lever 29. The lower end of this carrying lever is pivoted at 32 near the bottom of 30 the casing. A leg 34 for actuating this carrier arm is mounted on and connected to the short transverse shaft 35. The lower end of this leg is provided with an enlargement or 35 foot having a recess 36 at the rear thereof adapted to engage a pin 37 on said carrier arm. The bottom 38 of the foot is formed on the radius of a circle and a small toe or stop 39 is provided on the opposite end of the foot whereby a rearward movement of 40 the leg from its normal position, as illustrated in Figure 1, first throws the carrier arm 29 back against the tension of spring 33 to the beginning of its feeding stroke after which the pin 37 is withdrawn from the 45 notch 36 permitting the leg to continue its further movement due to the balance of the operating stroke of the plunger. As this leg is then returned under action of the spring 40 the extension 41 engages the pin 37 and 50 imparts to the lever 29 its advancing or operating stroke.

An arm 42 is connected to the leg 34 both being mounted on the transverse shaft 35. The free end of this arm extends into the

opening 18 on the plunger to control the 55 movement of the latter.

An operating handle 43 is also connected to this transverse shaft 35 whereby its movement in the downward direction actuates the plunger to cut off the stamp, and the pad 60 with its yieldable fingers to press and affix the stamp to the package. This downward movement also as above described moves the leg 34 backward and consequently the carrier lever to the commencement of its feeding 65 position. When the pressure on this handle is released the spring 40 returns the mechanism to normal which return stroke causes the feeding mechanism to advance the stamp strip the length of a stamp ready to be 70 severed and affixed by the next downward stroke of the plunger.

We have shown and described a spring 33 as acting on the lever 29 to draw it forward, but in practice we find that by placing a stop, 75 such as pin 44 back of said lever 29 to limit its backward stroke, it is sure to be engaged by the toe 41 and moved forward upon the forward movement of leg 34.

We claim:

1. In a stamp affixing machine, means for engaging the stamp strip to advance the same, a pivoted arm carrying said engaging means, a spring for giving said arm its feeding stroke, a pivoted actuating leg engaging 85 said carrier arm to return it after its feeding stroke, a plunger, a knife carried thereby, an arm connected to said actuating leg and engaging said plunger, and a hand-operating lever connected to operate both said arm 90 and leg.

2. In a stamp affixing machine, means for engaging the stamp strip to advance the same, a pivoted arm carrying said engaging means, a spring for giving said arm its feeding stroke, a transverse shaft, an actuating leg supported on said shaft and engaging 95 said carrier arm to return it after its feeding stroke, a plunger, a knife carried thereby, an arm connected to said actuating leg and 100 engaging said plunger, and a hand-operating lever also connected to said shaft for moving both of said arms.

In testimony whereof we affix our signatures.

EUGENE F. BOWEN.
EPHRIAM J. SCOTT.
